TERMINAL CONSTRUCTION

Newton C. Schellenger, El Paso, Tex., assignor to
 Chicago Telephone Supply Company, Elkhart,
 Ind., a corporation of Indiana

Application March 8, 1939, Serial No. 260,545

14 Claims. (Cl. 201—63)

This invention relates to a new and improved terminal construction and more particularly to such a construction adapted for use in connection with variable resistance devices.

My invention is especially applicable to variable resistance units employing resistance strips of carbonaceous type. Such units in general comprise a non-conducting base, with a resistance strip secured to the base, the strip consisting of a non-conducting support and a thin layer of conductive material sprayed or painted upon the upper face of the supporting material. The conductive layer usually comprises finely divided conductive material such as some form of carbon together with a binder and in some cases finely divided non-conducting material may also be included.

The variable resistance device includes a movable contact driven by a rotary shaft and a plurality of terminals by which the unit may be connected into the electrical circuit with which it is used. In some cases this may involve merely two terminals, one connected to the movable contact and the other to one end of the resistance strip. In other cases there is an additional terminal connected to the other end of the resistance strip. Some uses of the device require one or more additional tap terminals connected to intermediate portions of the resistance strip. Such uses occur in radio apparatus where it is desired to connect portions of the circuit to the resistance to provide a fixed bias or a potential difference between such portions of the circuit and portions connected to the end or ends of the resistance strip.

In many cases such taps must be electrically connected to portions of the resistance strip spaced a substantial distance from the end terminals. Where the tap terminal is located at the same point as the electrical tap, an extra extension of the base is required which increases the size of the device. Also in present day compact assemblies there may be difficulty in so positioning the device that wires may be readily soldered to the terminals at widely spaced points upon its periphery. It is therefore desirable to locate the tap terminal or terminals adjacent the other terminals of the unit even if the electrical tap connection is spaced from the terminal.

Terminals when secured to the base of the unit are located closely adjacent the supporting chassis when the unit is secured in place upon the chassis. This location may be undesirable for several reasons. Such terminals may be diffi-

cult to get at for soldering in compact assemblies. There is danger of shorting the terminals due to their becoming bent or due to excess solder. Also there may be undesirable capacity coupling between the terminals and a grounded metal chassis.

It is an object of this invention to provide a new and improved terminal construction adapted for use upon a tapped control in places where space limitations make it difficult or impossible to use an ordinary type of tap terminal construction.

Another object is to provide a construction in which contact between a tap and the conductive surface of a resistance element is maintained under pressure by the housing assemblies.

It is a further object to provide a construction which facilitates the assembly of a cover and insulating means in connection with a terminal.

It is also an object to provide a construction wherein a plurality of independent taps may be used at one time on a single device with the tap terminals located adjacent each other.

It is an additional object to provide a standard construction by which taps may be selectively connected to one of a plurality of portions of the resistance with the tap terminal in a single predetermined position.

It is a further object to provide a construction in which terminals may be secured in position without the use of separate securing means.

Other and further objects will appear as the description proceeds.

I have shown certain preferred embodiments of my invention in the accompanying drawings, in which—

Figure 1 is a face view of the variable resistance device with the cover partly broken away;

Figure 2 is an elevational view of the construction of Figure 1 showing the tap construction on the variable resistance device;

Figure 3 is a section taken on the line 3—3 of Figure 1, showing one form of insulator;

Figure 4 is a fragmentary section similar to Figure 3, showing another form of insulator;

Figure 5 is a fragmentary elevation of the insulator shown in Figure 4;

Figure 6 is a face view of a variation of a tap construction with the cover of the variable resistance device removed and the resistance element partly broken away;

Figure 7 is a plan view of the insulator shown in Figure 3;

Figure 8 is a plan view of the tap connecting

conductor with modifications represented in dotted lines;

Figure 9 is an enlarged fragmentary section of a modified form of terminal construction;

Figure 10 is a fragmentary plan view partly in cross-section, taken on the line 10—10 of Figure 9;

Figure 11 is a fragmentary elevation of the construction shown in Figure 9, as seen from the left;

Figure 12 is a fragmentary section of another modification of the terminal construction; and

Figure 13 is a fragmentary section of a form of construction of terminal adapted for use in connection with a movable contact.

Referring first to Figures 1 to 8, inclusive, the improved tap construction comprises a conductor 11 which may be formed from thin metal foil, such as copper, or other material having conductive properties. This conductor is positioned between the base 12 of the resistance device and the nonconductive face of the resistance element 13. This resistance element comprises a body of Bakelite, fibre or other non-conducting material with a resistance film or coating upon its upper face. In the present embodiment, the conductor is arcuate in shape and is adapted to underlie the outer portion of the resistance element. The conductor is secured to the base 12 at one end by means of the solder lug terminal 14 and the rivet 15. The terminal is secured to an extended portion 16 of the base 12. The other end of the conductor 11 comprises a laterally offset narrow portion 17 which is wrapped around a projection 18 of the resistance element 13 so that the end of the portion 17 lies upon the conductive face of the resistance element. The resistance element is provided with additional tap extensions 18—A and 18—B and, as shown in Figure 8, the conductor 11 may be made in suitable lengths for the different tap extensions as shown in broken lines at 17—A and 17—B.

The cover 19 is provided with a plurality of securing lugs 20, which interfit in the notches 21 in the edge of the base 12. The securing lugs are bent against the under face of the base or against a grounding plate 22 which may be provided to ground the cover to the metal bushing 23 which is secured to the base 12 and provides a bearing for the rotary shaft 24. This shaft 24 has the non-conducting drive plate 25 connected thereto and this plate drives the movable contact member 26. The member 26 is provided with the portions 27 engaging the upper face of the resistance element 13 and the portions 28 engaging the collector ring 29. The collector ring is provided with the terminal 65 and the ends of the resistance strip 13 have the fixed terminals 66 and 67 secured thereto. The details of construction of the variable resistance device are disclosed in my prior application, Serial No. 218,062, filed July 8, 1938, and form no part of the present invention. The lugs, as well as the notches in the base, are so positioned that one of each falls on either side of such points as the projections 18, 18—A and 18—B and ends 17, 17—A or 17—B of the conductor 11 may be located. Other lugs and notches may be located elsewhere as required for holding the cover in place. The side wall of the cover is cut out between the lugs adjacent the projections 18, 18—A and 18—B to a height approximating the combined thickness of the base 12,

the resistance element 18 and the insulator 30, as shown in Figures 2 and 3.

The insulator 30 may be formed from a strip of Bakelite, fibre or other non-conductive material. It will be noted that the notches 31 and projections 32 are substantially wedge-shaped. The notches provide recesses to receive the lugs 20, and the projections 32 fit between the cover lugs at the upper part of the cut-out portions 10 of the cover side wall. The inclined sides of the projections 32 prevent the insulator from becoming disengaged from the cover during assembly.

When assembled, the cover 19 is tightly held 15 in place by the lugs 20, which are positioned within the notches 21 and are bent under the base. The bottom edges of the cut-out portions of the cover side wall exert pressure on the projections 32 of the insulator, and the insulator 20 in turn bears down on the end 11 of the conductor 11 which lies upon the upper face of the projection 18 of the resistance element. The under surface of the conductor 11 is held in close contact with the projection 12 of the base. It is desirable to have 25 a slightly convex curvature to the bottom of the cut-out portion 33 of the cover side wall so that a greater pressure will be applied at the center of the insulator projection 32 than at its edges. 30 The form of construction shown in Figure 6 provides for two tap terminals upon a unit at the same time.

A modified form of insulator, as shown in 35 Figures 4 and 5, comprises a strip of flexible insulating material 34 of sufficient length to completely encircle the inside of the side wall of the cover or housing. It is desirable that the insulating material have sufficient resilience to maintain its position within the cover, although 40 other securing means may be employed. The strip 34 has notches 35 in alignment with those of the side wall; these notches, however, are not as deep as those of the side wall, consequently when the cover is in position the upper edge of 45 the strip 34 is in contact with the top of the cover, and the lower edge of the notches 35 exert a pressure on the conductor 17, as described in connection with the insulator shown 50 in Figure 7. It will be noted that the lower edge of the insulator notches 35 are slightly convex for the purposes set forth in connection with the cut-out portions of the cover side wall as shown at 33 in Figure 2.

Referring now to the form of terminal construction shown in Figures 9 to 11, an insulating plate 36 is placed upon the outer face of the metal cover 37 of the resistance device. A switch housing 38 is shown above the plate 36 and the means securing the switch in place serve also 60 to retain the plate in position. The construction may be used independently of the switch, however. The plate 36 has an extended portion 39 which projects beyond the side walls of the cover at such point as a terminal lug 40 may be 65 positioned. The solder lug portion 41 of the terminal 40 projects through a slot in the extended portion 39. This slot is sufficiently wide to allow the head of the lug to pass through, but the shoulder 42 abuts against the under side of 70 the portion 39 and retains the parts in proper position. Above the shoulder 42 is a second shoulder 43 having a width approximating that of the slot and which positions the lug in the slot. The terminal 40 is formed of sheet metal, and has an integral contact portion 44.

The contact portion of the terminal 40 is folded inwardly under the insulating segment 45, and the end 46 of the terminal is bent upwardly against the inside of the segment. The notches 47 and 48 in the segment 45 provide locating recesses for the terminal 40 and serve as a means for positioning the terminal with respect to the assembly. The notch 47 in the forward edge of the segment may be deeper than the thickness of the conductor, while the notch 48 in the rear edge is preferably equal to the thickness of the conductor. The segment also has shoulders 49 which rest against the outside of the cover 37 and prevent the segment from moving inwardly toward the metal cover 37. The under surface of the contact portion 44 is held in engagement with the conductive coating of the resistance element 13, which in turn is supported by the base 12. The base and resistance element have projections extending beyond the side wall of the cover at such point as the tap may be positioned, and serve as a support therefor.

The cover 37 has a cut-out portion 50 of a width approximating the distance between the shoulders 49 and a height equal to the combined thickness of the conductor 44 and the insulating segment 45. The cover, as shown in Figures 9 and 10, is provided with an insulating strip 51 which fits within the side walls of the cover, as described in connection with insulation strip 34 of Figure 5. The strip has notches corresponding to those in the cover and aids in holding down the segment 45. The upturned end 46 of the terminal 40 engages the inner face of the insulating strip and thus prevents the terminal and segment from moving outwardly. The cover has securing lugs 52 which interfit in notches in the base, and are bent against the under face of the base 12 to maintain the parts in assembled relation.

The embodiment shown in Figure 12 is somewhat similar to that shown in Figures 9, 10 and 11. The terminal 53 is positioned within the cover 54 and the solder lug portion 55 projects through an opening 56 in the top of the cover. The insulating plate 57 is retained against the under side of the cover by the insulating strip 58 which also serves to insulate the terminal from the side wall of the cover. The lower end 59 of the terminal 53 is folded outwardly under the insulating segment 45 and the end is bent upwardly against the outside of the segment. The assembly is held together as set forth in respect to Figure 9.

Figure 13 shows a construction similar to that in Figure 9, as applied to the center terminal of a variable resistance device. The variable resistance device is similar to that shown in Figures 1 and 3. The center terminal 60, as shown, is formed integrally with a collector ring member 61 at its lower end and a solder lug portion 62 at its upper end. The intermediate depressed portion of the terminal fits in a cut-away portion of the base and maintains the parts in desired relation by preventing both radial and circumferential movement of the terminal. In this construction the resistance element does not have a projection overlaying the projection of the base 12, the conductor being held in direct contact with the base. In other respects the assembly is as described in connection with Figure 9.

While the constructions of Figures 9 to 12 show only a single terminal it will be understood that these forms of construction may be applied to a plurality of terminals in a single unit. This

form of construction, together with that of Figure 13, may be applied to all of the terminals of a unit to provide a device especially adapted for use where space is limited or where for any reason it is desired to have the terminals located above the housing for easy access.

All the forms of construction shown may be used to provide devices with tap connections, which devices are smaller in overall dimensions than devices with the tap terminal located at the point of electrical connection of the tap. The constructions all may be used to group the terminals to facilitate wiring or to so locate all terminals as to maintain them spaced from other elements of the circuit to minimize coupling of any kind. The constructions are also so designed as to provide a firm and permanent engagement between the resistance element and the terminals. This affords an efficient connection without the use of rivets which add to the cost of the device.

While I have shown certain preferred forms of construction, these are to be understood to be illustrative only, as the devices are capable of change and modification to meet varying conditions and requirements and I contemplate such variations as come within the spirit and scope of the appended claims.

I claim:

1. In a resistance device of the character described: a base; a resistance element on the base having an exposed conducting surface; a cover for the resistance device, positioned over said base and the resistance element; a terminal having an external part to which leads may be secured and having a portion engaging an area of the exposed conducting surface of the resistance element where the resistance element is supported by the base; an insulator engaging said portion of the terminal so that said terminal portion is interposed between the insulator and the conducting surface of the resistance element, part of said cover engaging the insulator directly over the contacting portions of the terminal and resistance element and consequently over the support provided by the base so that pressure on the cover toward the base clamps the terminal portion against the resistance element and establishes good electrical connection therebetween solely by the attachment of the cover to the base; and means for drawing the cover and base together and holding the same assembled.

2. In a resistance device of the character described: a base; a resistance element on the base; a cover for the resistance device disposed over the base and the resistance element, said cover having a side wall; a terminal for the resistance element having a portion electrically and physically contacting the same; an insulator between the side wall of the cover and the terminal portion which contacts the resistance element so that pressure applied to the insulator by the side wall holds the terminal firmly to the resistance element; a second insulator supported by the cover and engaging another portion of the terminal to position the same; and means for maintaining a side wall of the cover in contact with the first named insulator under pressure.

3. In a resistance device of the character described: a base; a resistance element on the base and having an exposed conducting surface; a cover for the resistance device disposed over the base and the resistance element, said cover having a side wall; a metal terminal strip having a portion in electrical contact with the exposed

conducting surface of the resistance element and having an outer end portion extending out past the side wall; an insulator confined between the side wall and the first named portion of the terminal strip to hold the terminal strip on the resistance element; a second insulator supported by the cover and engaging the outer end portion of the terminal strip to position the same; and means for drawing the cover down onto the base and thereby clamping the first named insulator between the cover side wall and the terminal strip to press the terminal strip against the conducting surface of the resistance element.

4. In a resistance device of the character described: a base; a resistance element on the base and having an exposed conducting surface; a cover for the resistance device disposed over the base and the resistance element, said cover having a top and a side wall; an insulator within the cover overlying its side wall and abutting its top, the side wall and said insulator within the cover having aligned notches in their edge portions adjacent to the base with the notch in the side wall deeper than the notch in the insulator; a terminal member having a portion passing through the aligned notches and engaging the exposed conducting surface of the resistance element with a part thereof confined between the resistance element and the bottom of the notch in the insulator; and means for drawing the cover to the base to thereby press the terminal member against the exposed conducting surface of the resistance element and thus hold the terminal and resistance element together with a good electrical connection established therebetween solely by the attachment of the cover to the base.

5. A terminal construction for resistance devices comprising a base member, a cover for the base member having a top and side wall, an insulator within said cover overlaying said side wall and abutting said top, said insulator and side wall having cut-away portions in their margins adjacent to the base, a terminal member having an extremity entering said cut-away portion, a second insulator overlaying said terminal extremity and having a portion entering said cut-away portion, said second insulator having shoulders abutting the outside of said side wall and providing positioning means inside and outside of said side wall for said terminal extremity, and means cooperating with said cover and base for maintaining said first named insulator in contact with said second named insulator.

6. In a resistance device of the character described: a base of insulating material; a resistance element on the base, said resistance element having an exposed conducting surface; a substantially cup-shaped metal cover for the resistance device positioned over the base and the resistance element with the side wall of the cover engaging the base; a metal terminal having a portion overlying a small area of the conducting surface of the resistance element and having a part to which external leads may be attached, said portion of the terminal being adjacent to the side wall of the cover; an insulator overlaying said terminal portion, part of the cover engaging the insulator directly over the contacting portions of the terminal and resistance element so that pressure on the cover toward the base clamps the insulator, the terminal portion, and the adjacent portion of the resistance element between the cover and the base and establishes good electrical connection between the terminal

5 and resistance element solely by the attachment of the cover to the base; and means on the side wall of the cover engaging the base adjacent to the contacting terminal and resistance element portions and drawing the cover tightly toward the base.

7. In a resistance device of the character described: a base of insulating material; a substantially arcuate resistance element on the base having an exposed conducting surface; a substantially radial extension projecting outwardly from the resistance element, the exposed surface of the extension being electrically conductive and forming substantially a continuation of the conducting surface of the resistance element; a substantially cup-shaped cover engaged over the base and the resistance element and having a side wall disposed over and across the radial extension on the resistance element, the base having a portion thereof supporting said extension of the resistance element; a metal terminal having a portion engaging the conducting surface of said radial extension and having means to which external conductors may be attached; an insulator interposed between a part of the cover and said portion of the terminal and disposed over the contacting portions of the terminal and resistance element to press the terminal against the conducting surface of the resistance element and clamp the terminal and said radial extension of the resistance element between the insulator and the base upon the application of force on the cover toward the base; and means for drawing the cover tightly against the base to thereby hold said parts assembled.

8. In a resistance device, a base having an extended portion thereon, a resistance element overlaying said base, a cover for said device, an insulator overlaying said cover and having an extended portion, a terminal member having its lower extremity in contact with said resistance element, a second insulator overlaying the lower extremity of said terminal member adjacent to the extended portion of said base, means provided by the extended portion of the first named insulator for positioning the upper end of said terminal member, and means associated with said cover and said base for maintaining contact of said terminal element with said resistance element.

9. A terminal construction for an electrical control device having a base, a current carrying part on the base, and a cover disposed over the base, comprising: a metal terminal strip having a portion thereof physically and electrically contacting the current carrying part and having an outer end portion; insulated means for definitely positioning the outer end portion of the terminal strip with relation to the cover; non-conducting means engaging the terminal strip portion which engages the current carrying part and adapted to be pressed against said portion of the terminal strip by the cover upon its securing to the base; and means for securing the cover to the base.

10. In a resistance device of the character described: a resistance element on the base having an exposed conducting surface; a terminal having a part engaging said conducting surface; a cover for the device disposed over the base and the resistance element and having a notch in its edge adjacent to the terminal so as not to contact the same; an insulator engaging the terminal and having a projection

disposed within said notch to be confined between the bottom of the notch and the terminal; and means for drawing the cover to the base to clamp the terminal against the resistance element.

11. In a resistance device of the character described: a base; a resistance element on the base and having a projection thereon overlying the base; a conductor between said resistance element and the base and having an extremital portion overlying said projection of the resistance element; a cover for the device disposed over the base and the resistance element with a part of the cover extending across said extremital portion of the conductor; an insulator between said part of the cover and the extremital portion of the conductor; and means for drawing the cover to the base to clamp said parts together with the extremital portion of the conductor firmly engaging the top of the resistance element.

12. In a resistance device of the character described: a base; a resistance element on the base and having an exposed conducting surface; a terminal member having a part engaging said conducting surface; a cover for the device disposed over the base and the resistance element thereon and having a part thereof crossing the terminal adjacent to its portion which engages the exposed conducting surface of the resistance element; an insulator interfitting with the cover and having a convex surface engaging the terminal member to press the same against the resistance element; and means for drawing the cover to the base so as to apply pressure on the insulator for pressing the terminal member against the resistance element.

13. In a resistance device of the character described: a base; a resistance element overlying the base and having an outward projec- 40

tion thereon; a terminal for the resistance element having a part wrapped about said projection to dispose a part thereof between the projection and the base and another part thereof over the projection of the resistance element; a cover for the resistance device disposed over the base with a part thereof crossing said projection; a pressure applying non-conducting connection between the cover and the part of the terminal disposed over the projection on the resistance element; and means for drawing the cover to the base to press the terminal against said projection to establish good electrical connection therebetween and also clamp said projection against the base to thus hold the resistance element and the terminal to the base at the location of said projection.

14. In a resistance device of the character described: a base of insulating material; a resistance element on the base having a non-conducting bottom and a conducting top surface; a projection on the resistance element; a terminal strip disposed between the non-conducting bottom surface of the resistance element and the base, part of said terminal strip being folded over said projection to engage the top conducting surface thereof; a cover for the resistance device disposed over the base and resistance element, said cover having a part adapted to press the folded portion of the conductor firmly against the conducting surface of the resistance element projection upon attachment of the cover to the base; means for drawing the cover to the base; and a terminal part on the conductor remote from its portion which is folded over the projection on the resistance element and extending outside the cover for the attachment of leads thereto.

NEWTON C. SCHELLENGER.
